WRIGHT & SAWYER.

Carriage-Top.

No. 21.391.

Patented Aug. 31, 1858.

UNITED STATES PATENT OFFICE.

D. B. WRIGHT AND L. SAWYER, OF SOUTH AMESBURY, MASSACHUSETTS.

ATTACHING THE PROPS OF CARRIAGE-BOWS.

Specification of Letters Patent No. 21,391, dated August 31, 1858.

To all whom it may concern:

Be it known that we, D. B. WRIGHT and L. SAWYER, of South Amesbury, in the county of Essex and State of Massachusetts, have 5 invented a new and useful Improvement in Attaching Props to Carriage-Bows; and we do hereby declare that the following is a full, clear, and exact description of the same, reference being had to the annexed drawings, making a part of this specification, in 10 which—

Figure 1, is a longitudinal section of a portion of a carriage bow with our improvement attached to it, showing a side view 15 of ditto. Fig. 2, is an end view of our improvement. Fig. 3, is a longitudinal section of a portion of a carriage bow with the usual prop attached to it.

In Figs. 1 and 2 similar letters of reference indicate corresponding parts.

To enable those skilled in the art to fully understand and construct our invention we will proceed to describe it.

A, Fig. 1, represents a portion of a carriage bow, and B, is a metal plate which is "let into" the outer surface of the bow, so that the outer surface of the plate will be flush with the outer surface of the bow. The plate B, has a nut (a) at its center. 25 30 This nut (a) is formed by having a projecting shell on the inner side of the plate said shell having an internal screw thread.

C, represents the prop which is of the usual form with the exception that a screw (b) is formed at its inner end and also a shoulder (c) the latter being somewhat larger in diameter than the screw (b) as plainly shown in Fig. 1. The screw (b) is made to fit the nut (a) of the plate B, and 35 40 when fully screwed into said nut the shoulder (c) bears against the plate B.

The shoulder (c) is designed to be about equal in width to the leather or covering D, which is fitted over the several bows of 45 the top the covering being of course over the plate B. A hole (d) somewhat larger in diameter than the shoulder (c) is made through the covering D, opposite the nut (a) to allow the screw (b) to pass through. 50 The screw (b) is then screwed into the nut (a) and the prop is secured to the bow.

In Fig. 3, the usual mode of attaching the props to the bows is shown. In this case the prop E, is cast or formed with a plate 55 F, through which screws (d) pass into the

bow G, and through the covering H. The covering H, therefore it will be seen is rigidly attached to the bow at the point where the prop is attached consequently the covering is liable to wrinkle and is also subjected to considerable strain as the top is raised and lowered as it is not permitted to adjust itself. By our improvement this difficulty is avoided as a requisite degree of play or movement is allowed the leather or covering in consequence of the hole (d) being larger in diameter than the shoulder (c). Our improvement when attached to the bows have a much neater appearance than the ordinary props, and they may be readily detached so as not to interfere or offer any obstruction to workmen in finishing or in "bending off" the top. Indeed the facility which our invention offers for the finishing or bending of the top, constitutes a leading 60 65 70 75 80 advantage of our invention.

We are aware that props have been invented in which the prop and plate are cast together, and the plate "let in" to the bow, so as to be flush with the surface thereof; 85 an independent shoulder piece being provided, which screws over the prop after the leather has been applied. This device is liable to serious objection from the fact that the leather must be strained over the projecting end of the prop—a thing which it is impossible to do with nicety, for there will be more or less wrinkling. It is moreover very difficult to cut the aperture through which the prop is to pass, with exactitude, 90 95 owing to the presence of the projecting prop. The latter prevents the operator from stretching the leather snugly against the bows, so that the cutting must be done, to a certain extent by guess-work. Considerable time is also lost in the endeavor to obtain a tolerable degree of nicety, and the leather is not unfrequently torn by catching, during the straining, upon the points of the props. All such difficulties are avoided by the use 100 105 of our improvement. The prop being separate and independent of the plate, the latter is first "let in" flush with the surface of the bow; the leather is then stretched snugly over the bows, when the holes may be immediately and accurately cut with a knife, and the props C, may be then screwed home.

The superior advantages of our improvement, when the leather requires removal for repair, &c., will be obvious.

We do not claim the employment of a movable shoulder-piece which screws upon the prop, as in C. Thomas's patent. But

5 We claim and desire to secure by Letters Patent, as an improved article of manufacture—

A carriage prop, in which the prop C, is rendered independent of its plate B, sub-

stantially as and for the purposes herein set forth.

D. B. WRIGHT.
L. SAWYER.
